(57) **CLAIM**

The ornamental design for a pharmaceutical ingredient mixing training device, as shown and described.

DESCRIPTION

FIG. 1 is a top, left, front perspective view of a pharmaceutical ingredient mixing training device according to our design;

FIG. 2 is a bottom, right, rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 a top plan view thereof; and,

FIG. 8 is a bottom plan view thereof.

The broken line portion of the figure drawings is included to show unclaimed subject matter only for the purpose of illustrating environment and forms no part of the claimed design.
